COMBINATION RING AND BAR TRAVELER
SPINNER AND TWISTER RING

Louis W. Schaaff, Jackson Heights, N. Y., assignor of fifty-two per cent to Wilhelmina M. Kuhn, New York, N. Y.

Application October 9, 1935, Serial No. 44,173
Renewed November 20, 1939

5 Claims. (Cl. 57—119)

This invention relates to spinner and twister rings for use with bar and ring travelers and to spinning devices including in a novel combination my improved spinner and twister ring and a traveler of either the ring or bar type, which traveler may advantageously be formed with ring-contacting running surfaces of non-metallic material requiring no lubrication, such as, for example, the travelers of my prior Patent No. 1,834,874.

A principal object of this invention is to provide a spinner and twister ring that is adapted for use with either ring type travelers or bar type travelers interchangeably, without requiring any change of or adjustment to the ring, thus saving the labor, time and loss of production which would be involved otherwise to change the rings when a change from either type of traveler to the other becomes necessary or is desired; in other words this object of the invention is to provide a single unitary spinner and twister ring which is a permanent combination of ring suited to the ring type travelers and a ring suited to the bar type traveler.

Another object of this invention is to provide a spinner and twister ring of the character described which is adapted to contact substantially only a single point of a ring traveler, and only a single point on each foot of a bar traveler, when the traveler is running thereon, and to have the traveler make edgewise contact against the track surface of the ring, and thus to lessen friction and to make for smoother running with less and more uniform tension and permit operation at higher speeds, resulting in faster production, without increase in the power load.

Another object of this invention is to provide a spinner and twister ring which prevents the track from being contaminated by emulsion, dirt or other foreign matter that may be thrown off from the thread during operation.

The objects of this invention, accordingly, include the provision of a spinner and twister ring which greatly reduces equipment cost for rings and travelers, produces a saving in operating costs and increases the available operating time and production, since less frequent stoppage of the spindles is necessary for replacement, cleaning of rings and travelers, or for leveling, repairs or tying of broken threads, than heretofore, and produces a greater uniformity in the twist of the yarn, both with ring type travelers and with bar type travelers.

Other objects of this invention will be in part obvious and in part pointed out hereinafter.

In order that a clearer understanding of this invention may be had, attention is hereby directed to the accompanying drawing, forming a part of this application, and illustrating certain possible embodiments of this invention, and in which:

Fig. 1 is an elevation, partly in section, of certain portions of a spinning device, showing a spinner ring embodying this invention, and a ring traveler adapted to the ring; 10

Fig. 2 is a plan view of the construction shown in Fig. 1;

Fig. 3 is a detail view of the ring and traveler shown in Fig. 1;

Fig. 4 is a sectional view showing a modified 15 construction of the ring and a bar traveler adapted thereto.

In the drawing the travelers are depicted as in the positions they assume when running.

Similar reference characters refer to similar 20 parts throughout the several views of the drawing.

Referring to the drawing, the spinner and twister ring embodying my invention is shown as shaped to form a depending annular lip 1 having 25 a smooth, rounded traveler track surface 2 extended downwardly, and adapted to be engaged with rocking contact by the traveler 3 at point 4 or its inner edge portion which has greater curvature than the curvature of the nose surface 30 2. In Fig. 4, showing a bar traveler 5, the curved contacting edge portion of the foot of the traveler is indicated at 6.

As shown in the drawing, the lip 1 of the ring may comprise the lower edge of an annular flange 35 or wall 7 which is inclined inwardly and downwardly at a steep angle (52° to the horizontal in the drawing). Flange 7 is supported by an annular wall portion 8 which extends downwardly from adjacent the upper edge of flange 7 at 40 approximately right angles thereto and terminates in an annular base portion 9 which is lower than the lower edge of flange 7 and is secured to the attachment ring 10 of the ring assembly, as by being frictionally engaged against a shoulder 11 on ring 10 and seating on a portion 12 of the ring, as shown in Fig. 3. If desired, the meeting faces of the portion 9 of the spinner ring and the shoulder 11 of the attachment ring 10 may be provided with complementary threads 50 (not shown) and the parts screwed together. Sufficient space is provided between the lip 1 and the upper surface of the body of ring 10 so that the traveler will run absolutely freely therebetween. To this end the upper surface of ring 55

- 10 may be formed to have a hollow or groove 14. An annular vertical wall or flange 15 is provided about the inner edge of ring 10 and extends sufficiently high above the level of the traveler track 5 2 to intercept emulsion or other foreign matter thrown from the thread toward the track, and thus prevents such emulsion, rust, acid and other foreign matter from reaching the track, and keeps the track clear of contamination.
- 10 As shown in Fig. 3, the ring traveler is substantially in the shape of a C and embraces the wall 7. The lower end 16 of the traveler extends well under the lip 1, and its upper end 17 hooks over a ridge 18, constituting the upper edge of 15 flange 7. Thus the traveler cannot be jerked from the ring or fly away therefrom. When the traveler is running its upper portion 17 and its body, as well as its lower extremity 16, are spaced from and do not contact any part of the spinner ring, 20 the only point of contact being the contact mentioned before between the rounded surface 2 of the lower lip 1 of the ring and the wider curved surface 4 of the traveler. This point of contact is a fulcrum point on which the traveler may rock 25 upwardly until its inner periphery meets the ring flange 7 at or near the ridge 18, and the traveler may rock downwardly until its end 17 strikes the wall 8. Upper end 17 of the traveler is sufficiently short so as not to strike the flange 8 at any 30 time when the traveler is running.

The thread guide 20 of the traveler is so positioned on the traveler that when the traveler is running it is approximately in vertical line with the contact point between the ring and traveler 35 and is connected with the traveler at such a place that the combination of the action of the centrifugal force and the pull of the thread 30 maintains the traveler out of contact with the ring except at the contact or fulcrum point, and the 40 contact at this point will be extremely slight and approximately frictionless. When the ring traveler is at rest its lower portion seats in groove 14 of the ring and end 17 engages ring ridge 18, thus preventing the traveler from becoming disengaged from or falling off the ring flange 7 and maintaining the traveler upright, facilitating 45 easy and smooth pick up and starting with a minimum of friction and strain.

From the above it will be readily appreciated 50 that in accordance with my invention the single floating contact between the ring traveler and the ring has decidedly less friction than is possible with prior constructions wherein both ends of the traveler engage beneath the opposite 55 flanges of the ring with considerable force and friction. Practically no force is required to pick up and start the traveler in my construction, the play is absolutely free in my construction and the track of the ring is prevented from being 60 contaminated by rust, emulsion and other foreign matter thrown off the thread, which is not the case with the usual prior constructions.

Similarly, when bar travelers are used with 65 rings embodying my invention each end of the traveler has contact with the ring at one point only, whereas in the usual prior constructions the end of the bar traveler contacts the track flange of the ring both at its tip and at an intermediate surface. Thus, with bar travelers, as 70 well as with ring travelers, my invention reduces the frictional contact between the ring and the travelers and secures the improvements and advantages more specifically pointed out hereinbefore, as well as other improvements and ad-

vantages which will be understood and appreciated readily by persons familiar with this art.

Spinner rings and travelers embodying my invention may be made of any suitable material with the track surfaces having a hard and smooth 5 finish. However, the travelers, or at least the contact portions thereof, are preferably made of fiber or the like, since by the use of such materials no lubrication is necessary, and all the disadvantages of and objectionable features connected 10 with lubrication, are avoided.

As many changes could be made in the above construction, and as many apparently widely different embodiments of this invention could be made without departing from the scope thereof, 15 it is to be understood that all matter contained in the foregoing description or shown in the accompanying drawing be interpreted as illustrative and not in a limiting sense.

What I claim is:

1. A spinner and twister ring of the character described including an annular member having an annular flange inclined downwardly and inwardly, the lower edge of said flange constituting a traveler track, a base portion presenting a 25 concave upwardly facing surface, a supporting wall extending downwardly from adjacent the upper edge of said flange to said base portion throughout the circumference of said base portion, and an annular ridge along the upper edge 30 of said flange protruding outwardly of the supporting wall.

2. In a spinning device of the character described, a spinner and twister ring having an annular flange inclined downwardly with the lower edge of the flange constituting a traveler track, a member having a concave upwardly facing annular surface located beneath said track and an inner wall spaced inwardly from said track and extending above the same in combination 35 with a traveler having a portion extending downwardly between said flange and said inner wall and formed with a lower hook-shaped end extending beneath said track and conforming generally to the contour of the concave annular 40 surface of said member whereby the traveler when at rest, tends to assume a position similar to that assumed thereby during operation.

3. In a spinning device of the character described a spinner and twister ring presenting a 50 downwardly extending flange the lower edge of which constitutes a traveler track, a member having a concave upwardly facing annular surface beneath said track and a wall spaced inwardly from said track and extending above the 55 same, in combination with a bar traveler having end portions extending downwardly between said track and wall and with hook-shaped lower ends extending beneath said track and conforming generally to the contour of said concave annular 60 surface whereby said traveler when at rest engages said annular surface and said wall and is held in an upright and operative position.

4. A spinner or twister ring adapted for use with either a ring or a bar traveler and serving 65 to retain the traveler when at rest in a position permitting ready starting thereof, said ring comprising an annular member having a flange extending inwardly and downwardly with the lower edge thereof constituting a traveler track, an 70 annular wall located inwardly of said track and extending above the track in a position to intercept emulsion or other foreign matter thrown off from the thread toward the track and a base member presenting an annular concave upwardly 75

facing surface located beneath said traveler track and cooperating with said annular member to maintain a traveler when at rest in substantially a vertical position and cooperating with said annular wall to maintain said traveler in an upright and operative position.

5. A spinner or twister ring adapted for use interchangeably with either a ring traveler or a bar traveler, said ring comprising an annular flange inclined inwardly and downwardly with the lower edge thereof rounded to constitute a traveler track, a support for the flange connected thereto below the upper edge of said flange and extending outward and downward therefrom to form a recess behind the traveler track and between the track and support within

which recess the extremity of a traveler engaging said track may extend and move freely during operation without engaging the inner surface of the support, means presenting a concave upwardly facing surface located beneath and generally parallel to the rounded surface of the traveler track and a member located inwardly of the traveler track and extending above the same, said upwardly facing concave surface serving as a support for the traveler and cooperating with said upwardly extending member to maintain a bar traveler when at rest in an upright and operative position and cooperating with the upper edge of said flange to hold a ring traveler when at rest in an upright and operative position.

LOUIS W. SCHAAFF.
